DRINK MIXER

Filed March 1, 1922

UNITED STATES PATENT OFFICE.

RAYMOND B. GILCHRIST, OF NEWARK, NEW JERSEY, ASSIGNOR TO THE GILCHRIST COMPANY, OF NEWARK, NEW JERSEY, A CORPORATION OF NEW JERSEY.

DRINK MIXER.

Application filed March 1, 1922. Serial No. 540,190.

To all whom it may concern:

Be it known that I, RAYMOND B. GILCHRIST, a citizen of the United States, and a resident of Newark, in the county of Essex and State of New Jersey, have invented certain new and useful Improvements in Drink Mixers, of which the following is a full, clear, and exact description.

The invention relates to drink mixers. In machines for this purpose, the liquid constituents of the drink to be mixed are usually poured into a receptacle which is generally designated a "shaker," from many different containers disposed away from the mixer. The receptacle, with these constituents therein, is brought to the mixer and placed in operative relation thereto and is removed from the machine after each mixing operation to discharge its contents. This is rendered necessary, because so many different ingredients and flavors are used in making drinks that they are, in nearly all cases, mixed individually. It is usually necessary to run the agitator for a considerable period to properly blend or mix the constituents and, therefore, it is desirable that provision be made for retaining the receptacle and agitator in operative relation to permit the dispenser to perform other duties during the mixing operation. In drink mixing, it thus becomes necessary to frequently place the receptacle containing the constituents into cooperative relation to the agitator and to withdraw it from the machine to discharge its contents and cleanse the receptacle between mixing operations.

A desideratum in this art is to expedite and simplify the operations necessary to bring the receptacle and agitator into cooperative relation, to maintain them in such relation, in starting and stopping the motor, and in the removal of the receptacle to avoid the necessity of manually manipulating the receptacle into operative position and withdrawing it therefrom and to additionally perform some separate step or operation, such as lowering the motor and agitator together, or shifting the agitator and its shaft into the receptacle and relatively to the motor, or raising and locking a receptacle support to establish and maintain cooperative relation of the receptacle and agitator or to control the operation of

the machine. Another desideratum in this art is to simplify the machine by dispensing with movable connections in and for the mechanism for driving the agitator.

One object of the present invention is to provide an improved drink mixer in which these additional operations or steps are dispensed with and in which manual shift of the receptacle is utilized to completely control the operation of the machine and the securing of the receptacle and the agitator in cooperative relation. By dispensing with the necessity of these additional steps or operations, the time of the dispenser in performing them is saved and the service is improved.

Another object of the invention is to provide a receptacle controlled machine which is equipped so that the receptacle can be manipulated to control its locking into operative position around the agitator, its release for withdrawal, and the starting and stopping of the motor.

Another object of the invention is to provide a machine of this type in which movable connections in and for the driving mechanism for the agitator are dispensed with.

Another object of the invention is to provide a machine which is simple in construction, which may be easily and readily operated and which is efficient in operation.

Other objects of the invention will more fully appear from the following description.

The invention consists in the several novel features hereinafter set forth and more particularly defined by claims at the conclusion hereof.

In the drawings: Fig. 1 is a section of a machine embodying the invention, parts being shown in elevation, the receptacle being shown in operative position. Fig. 2 is a similar view showing the receptacle removed from its holding means. Fig. 3 is a perspective of the slidable holder for the receptacle and its guideway. Fig. 4 is a section taken on line 4-4 of Fig. 1. Fig. 5 is a perspective of the supporting ledge and inclined guide for the receptacle.

The invention is exemplified in a machine comprising an electric motor 8 which is supported at the upper end of a standard 9 which is channelled in cross-section and

serves as a stationary support for the motor. Its lower end is rigid with a base 10 which is usually adapted to rest on a counter or table. A shaft 11 secured to the rotor of the motor projects downwardly from the motor case and is provided at its lower end with a suitable agitator 12 for mixing the constituents of a drink, as well understood in the art. Shaft 11 is of sufficient length so that the agitator may be disposed in the constituents of a drink to be mixed near the bottom of an open-topped receptacle 19 held below the motor and containing said constituents. There is sufficient clearance below the agitator to permit the receptacle 19 to be placed beneath and around the agitator without spilling its contents and without the necessity of lowering the agitator into the receptacle. In the present invention the relationship between the agitator and the motor or between the agitator and the base are not varied and the receptacle only is manipulated in establishing cooperative relationship between the receptacle and the agitator so that movement of the agitator or the agitator and motor are not necessary for this purpose. The case of the motor 8 is rigidly secured by screws 13 to lugs 14 which are integral with the upper end of the standard. A case 15, containing an electrical switch of usual construction and having its members connected to control the motor 8, is fixedly secured to the outside of the motor-casing of the motor. A spring-pressed button 16 operates the switch in the case 15 to close the circuit and cause the motor 8 to run while the button is pushed upwardly and to open said circuit to stop the motor when the button is released. The switch-members in the case 15 may be of standard construction, as well understood in the art, so that detailed illustration has not been deemed necessary. A pair of yielding contact-strips 16^a, adapted to enter a switch-socket of usual construction, project rearwardly from the case 15, so that the necessary electrical connections to supply current to the motor will be made by pushing an ordinary conductor socket which is adapted to receive said contact-strips and is connected by a flexible cord conductor to a suitable source of energy, into connected relation with said strips.

The lower portion of the standard 9 is provided with a backwardly and upwardly sloping or inclined front face 14 which is arcuate in cross section, conformably to the periphery of the receptacle to form a guideway or surface over which the receptacle will freely slide in its movement to and from its operative position around the agitator. A slot 15 is formed in the standard 9 above the guideway 14 to form a guideway or track for a slidable holder 16'. The sides of holder 16' are formed with grooves 18 to receive the margins of the slot 15 and slidably retain the holder in the standard. This holder is slidable to guide the upper end of the receptacle while it is raised into and lowered from its operative position, so that the receptacle cannot strike the agitator while it is being placed into and removed from its operative position. This holder is also adapted to lock the upper portion of the receptacle while it is supported in operative position. For these purposes, the holder 16' is formed with an arcuate groove 18' conforming transversely to the wall of the receptacle, adapted to receive one side of the upper margin or rim of the receptacle and hold it locked against lateral movement in any direction. In front of the groove 18', the holder is provided with a hook or member 17 which is adapted to extend into the upper portion of the receptacle at one side thereof and to engage its inner periphery. The upper portion 20 of the rear face and the lower portion 20^a of the front face of groove 18' are inclined upwardly and rearwardly to permit limited tilting of the receptacle when its lower end is free in effecting the removal of the receptacle from the groove and to permit its insertion therein. The lower portion 21 of the back face below inclined portion 20 and the upper vertical portion 20' of the front face of groove 18' are disposed to cooperate and lock the receptacle when it is supported from below in its vertical and operative position. The lower portions of the faces of the groove 20 are flared to direct the upper rim of the receptacle into the groove. By forming the faces of the groove so that only a limited movement of the receptacle is possible, the latter will be secured, so that it cannot be tilted into position to cause it to strike the agitator during its insertion and removal. Holder 16' will be automatically raised by the receptacle and lowered therewith. At the upper end of guide 14, a ledge 22 with an arcuate back 22^a conforming to the periphery of the receptacle, is provided to form a rest or seat for the lower rim of the receptacle, and a rearwardly and downwardly inclined shoulder 22^b, adapted to engage the inner edge of the lower rim of the receptacle, is adapted to hold the lower rim of the receptacle on said seat and so that, when the upper portion of the receptacle is locked in the holder 16', the entire receptacle will be securely locked in operative position.

A lever 23, for operating the switch-button 16 to control the operation of the motor 8, is pivoted to the standard by a pin 24 has its upper end formed with a cam 25 to shift button 16 upwardly, extends through a guide-way 26 in the vertically slidable holder 16', and is provided with a cam portion 27 which is acted upon by the

front and rear edges of said guideway to shift the lever forwardly and backwardly as the holder 16' is lowered and raised to cause the lever to operate the switch-button 16^b into position, to close and open the switch for controlling the motor 8. A stop 28 is provided on lever 23 to limit the downward movement of the holder. The receptacle illustrated is provided with an upper 10 wear-band 30 and a lower wear-band 31.

The operation will be as follows: Assuming the machine to be idle, the holder 16' will be held in its lowered position, as illustrated in Fig. 2. The operator will place 15 the receptacle against the arcuate guide-face 14 and slide it upwardly thereon. This will cause the upper rim of the receptacle to enter groove 18 in holder 16' at an angle and so it will be substantially parallel to the 20 inclined faces 20 and 20^a of said groove. When the upper rim has entered the arcuate groove, said inclined faces will limit the 25 tilting and also the lateral movement of the receptacle, so that it cannot strike the agitator while it is being raised into and lowered from its operative position. The operator, continuing the manual lift of the 30 receptacle, will raise the holder, the lower portion of the receptacle sliding on the guide-face 14 while its upper portion is secured in the holder 16'. When the holder strikes the upper end of slot 15, it will be 35 arrested and, at such time, the bottom of the receptacle will have cleared the lug 22^b on ledge 22. The operator, exerting a backward pressure upon the receptacle will force 40 its lower end against the back face 22^a of seat 22 and then release the receptacle. Thereupon, the lower rim will pass into 45 locked relation with the lug 22^b to lock the lower portion of the receptacle on the seat 22 and holder 16' will follow the receptacle and lock its upper portion against movement in any direction. Holder 16', during 50 its lift by the receptacle, will, through cam 27 and guide-way 26, shift the lever 23 backwardly to lift button 16 and close the switch for the motor 8, so that the agitator will commence to rotate before the receptacle is 55 locked in its operative position. Lever 23 will continue to hold the switch-button in position to cause the motor to run as long as the receptacle remains in the machine. When the mixing operation has been completed, the operator will grasp receptacle 60 19, raise it slightly, then tilt it forwardly sufficiently to clear lug 22^a and lift it off ledge 22. The tilting movement of the receptacle is positively limited by the inclined 65 surfaces at the back and front of groove 18 in the holder, so that the vessel cannot be tilted excessively and strike the rotating agitator. Then, the operator will manually lower the receptacle and during such lowering movement, the holder 16' will be inter-

locked with it, so that it will be positively lowered thereby until it is arrested by stop 28. During this lowering movement, the holder 16' will act upon cam 27 to shift lever 23 to release button 16 and cause the 70 motor to stop at the desired predetermined time. By continuing the lowering of the receptacle after the holder 16 has been arrested, the upper rim of the receptacle will be withdrawn from the holder and released 75 for withdrawal from the machine.

The invention exemplifies a machine of the character described, in which the upper rim of a vessel is positively guided while it is manually shifted into and out of operative 80 position; in which the receptacle will be secured and guided so that it will not strike the agitator while it is being placed into and removed from its operative position; in which the receptacle is adapted by its own manipulation to be locked into and released from its operative position; in which the receptacle positively operates a switch-lever to control the operation of the motor; in which the supporting standard or column 85 and the receptacle guide and a stationary member of the automatic receptacle-guiding-means are formed integrally, which materially simplifies the construction, and avoids the necessity and cost of a column which 90 is separate from the stationary-support and guide; and which is simple in construction.

The invention is not to be understood as restricted to the details set forth, since these 100 may be modified within the scope of the appended claims, without departing from the spirit and scope of the invention.

Having thus described the invention, what I claim as new and desire to secure by Letters Patent, is:

1. In a machine of the character described, the combination of a motor, an agitator driven thereby and supported from above with sufficient clearance to permit a receptacle with an open top to be placed into operative position around the agitator, and vertically movable means to engage the upper margin of the receptacle and hold it while it is being manually shifted.

2. In a machine of the character described, the combination of a motor, an agitator driven thereby and supported from above with sufficient clearance to permit a receptacle with an open top to be placed into operative position around the agitator from below, and vertically movable means to engage the upper margin of the receptacle at one side thereof and to hold it while it is being manually shifted to and from its operative position and while in said position.

3. In a machine of the character described, the combination of a motor, an agitator driven thereby and supported from above with sufficient clearance to permit a receptacle with an open top to be placed into oper-

ative position around the agitator, and a vertically movable holder adapted to engage the inner and outer sides of the upper portion of the receptacle.

- 5 4. In a machine of the character described, the combination of a motor, an agitator driven thereby and supported from above, the agitator being supported with sufficient clearance to permit a receptacle with an 10 open top to be placed into operative position around the agitator, and a vertically movable holder for and shiftable by the receptacle, provided with means to permit limited pivotal movement of the receptacle in the 15 holder.

5. In a machine of the character described, the combination of a motor, an agitator driven thereby and supported from above, with a sufficient clearance to permit a receptacle with an open top to be placed into operative position around the agitator, and a 20 holder movable by the receptacle and formed to straddle one side-portion of the upper rim of the receptacle.

- 25 6. In a machine of the character described, the combination of a motor, an agitator driven thereby and supported from above with sufficient clearance to permit a receptacle with an open top to be placed into operative 30 position around the agitator, a vertically movable holder for the upper margin of the receptacle, and a stationary guide for the lower portion of the receptacle.

7. In a machine of the character described, 35 the combination of a motor, an agitator driven thereby and supported from above with sufficient clearance to permit a receptacle with an open top to be placed into operative position around it, a vertically movable holder adapted to be engaged and shifted by the upper rim of the receptacle, and a coacting support for the bottom of the receptacle to hold the receptacle in operative 40 position.

- 45 8. In a machine of the character described, the combination of a motor, an agitator driven thereby and supported from above with sufficient clearance to permit a receptacle with an open top to be placed into operative 50 position around it, a vertically movable holder having a groove therein to receive the upper margin of the receptacle, and a coacting bottom support to hold the receptacle in operative position.

- 55 9. In a machine of the character described, the combination of a motor, an agitator driven thereby and supported from above with sufficient clearance to permit a receptacle with an open top to be placed into operative 60 position around it, a vertically movable holder adapted to be engaged and shifted by the upper rim of the receptacle, and a coacting stationary bottom support disposed to hold the receptacle in operative 65 position.

10. In a machine of the character described, the combination of a motor, an agitator driven thereby and supported from above with sufficient clearance to permit a receptacle with an open top to be placed into operative position around the agitator, and a vertically shiftable holder adapted to be engaged and shifted by the top rim of the receptacle and to guide the receptacle into operative position, while it is manually supported. 70

11. In a machine of the character described, the combination of a motor, an agitator driven thereby and supported from above with sufficient clearance to permit a receptacle with an open top to be raised into operative position around the agitator, and a vertically shiftable holder having a groove to receive the top rim of the receptacle and a cooperating bottom support for the receptacle. 80

12. In a machine of the character described, the combination of a motor, an agitator driven thereby and supported from above with sufficient clearance below to permit a receptacle with an open top to be placed into operative position around the agitator, a vertically movable holder adapted to be shifted by and to guide the receptacle, and a cooperating support to lock the receptacle in its operative position, said holder and support permitting the receptacle to be automatically locked and released by its own manual manipulation. 90

13. In a machine of the character described, the combination of an electric motor, a support for said motor, an agitator driven by the motor and supported from above to rotate at a substantially fixed point relatively to the motor and with sufficient clearance to permit a receptacle with an open top to be raised around the agitator and manually placed into its position, means to automatically retain the receptacle upon its placement into such position comprising a movable member shiftable by the receptacle, and a switch for controlling the motor, operated by the receptacle to start the motor. 100

14. In a machine of the character described, the combination of an electric motor, a support for said motor, an agitator driven by the motor and supported from above to rotate at a substantially fixed point relatively to the motor and with sufficient clearance to permit a receptacle with an open top to be raised around the agitator and manually placed into its position, means to automatically retain the receptacle upon its placement into such position comprising a substantially stationary member and a movable member shiftable by the receptacle, and a switch for controlling the motor, operated by the receptacle to start the motor. 110

15. In a machine of the character described, the combination of an electric mo- 120

tor, a support for said motor, an agitator driven by the motor and supported from above to rotate at a substantially fixed point relatively to the motor and with sufficient clearance to permit a receptacle with an open top to be raised around the agitator and manually placed into its position, and means to automatically retain the receptacle upon its placement into such position comprising 10 a member whereby the upper portions of receptacles of different heights will be retained.

16. In a machine of the character described, the combination of an electric motor, a support for said motor, an agitator driven by the motor and supported from above to rotate at a substantially fixed point relatively to the motor and with sufficient clearance to permit a receptacle with an open top to be raised around the agitator and manually placed into its position, means to automatically retain the receptacle upon its placement into such position comprising a member shiftable by the receptacle, and a switch for controlling the motor, operated to start the motor by the receptacle through the shift of said movable member.

17. In a machine of the character described, the combination of a motor, an agitator driven thereby and supported from above with sufficient clearance to permit a receptacle with an open top to be placed into operative position around the agitator from below, means to automatically lock the receptacle in operative position when it has been manually shifted to such position, comprising a holder adapted to be engaged and shifted by the upper portion of the receptacle, and means for controlling the operation of the motor comprising a lever operated by said holder.

18. In a machine of the character described, the combination of a motor, an agitator driven thereby and supported from above with sufficient clearance to permit a receptacle with an open top to be placed into operative position around the agitator from below, means to automatically lock the receptacle in operative position when it has been manually shifted to such position, comprising a holder adapted to be engaged and shifted by the upper portion of the receptacle, and means for controlling the operation of the motor comprising a lever operated by said holder, the lever having a stop for the holder.

19. In a machine of the character described, the combination of a motor, an agitator driven thereby and supported from above with sufficient clearance to permit a receptacle with an open top to be raised into operative position around the agitator, a movable holder adapted to be engaged by the upper portion of the receptacle, and means for controlling the operation of the motor

comprising a pivoted lever having a sliding connection with and operated by said holder.

20. In a machine of the character described, the combination of a motor, an agitator driven thereby and supported from above, the agitator being supported with sufficient clearance to permit a receptacle with an open top to be raised into operative position around the agitator from below, and means to automatically lock the receptacle in operative position when it has been manually shifted to such position, comprising a vertically movable holder adapted to be raised by the receptacle and to hold the upper portion thereof. 70

21. In a machine of the character described, the combination of a motor, an agitator driven thereby and supported from above, the agitator being supported with sufficient clearance to permit a receptacle with an open top to be raised into operative position around the agitator from below, and means to automatically lock the receptacle in operative position when it has been manually shifted to such position, comprising a vertically slidable holder adapted to be raised by the receptacle and to hold the upper portion thereof. 80

22. In a machine of the character described, the combination of a motor, an agitator driven thereby and supported from above, the agitator being supported with sufficient clearance to permit a receptacle with an open top to be raised into operative position around the agitator from below, and means to guide the receptacle and automatically lock it in operative position when it is manually shifted to such position, comprising a vertically slidable holder adapted to be raised by the receptacle and to hold and guide the upper portion thereof. 95

23. In a machine of the character described, the combination of an electric motor, an agitator driven thereby and mounted in fixed relation to the motor with sufficient clearance to permit a receptacle with an open top to be manually placed into its operative position around the agitator from below, and means to automatically hold the receptacle upon its manual placement into its operative position comprising a vertically movable member operated by the manual shift of the receptacle. 110

24. In a machine of the character described, the combination of an electric motor, an agitator driven thereby and mounted in fixed relation to the motor with sufficient clearance to permit a receptacle with an open top to be manually placed into its operative position around the agitator from below, and means to automatically hold the receptacle upon its manual placement into its operative position comprising a vertically movable member shifted by the upper portion of the receptacle upon its manual 120 125 130

placement into the holding means and a member to extend under the receptacle.

25. In a machine of the character described, the combination of an electric motor, an agitator driven thereby and mounted in fixed relation to the motor with sufficient clearance to permit a receptacle with an open top to be manually placed into its operative position around the agitator from below, and means to automatically hold the receptacle upon its manual placement into its operative position comprising a hook movable vertically by the manual shift of the receptacle.

15 26. In a machine of the character described, the combination of an electric motor, an agitator driven thereby and mounted in fixed relation to the motor with sufficient clearance to permit a receptacle with an open 20 top to be manually placed into its operative position around the agitator from below, and means to automatically hold the receptacle upon its manual placement into its operative position comprising a vertically 25 movable hook operated by the manual shift of the receptacle and a stationary supporting member for the bottom of the receptacle.

27. In a machine of the character described, the combination of an electric motor, an agitator driven thereby and mounted in fixed relation to the motor with sufficient clearance to permit a receptacle with an open top to be manually placed 30 into its operative position around the agitator from below, and means to automatically hold the receptacle upon its manual placement into its operative position comprising a vertically movable member 35 operated by the manual shift of the receptacle, a switch for controlling the electric motor, and means for actuating the switch by the manual shift of the receptacle.

28. In a machine of the character described, the combination of an electric motor, an agitator driven thereby and mounted in fixed relation to the motor with sufficient clearance to permit a receptacle with an open top to be manually placed 40 into its operative position around the agitator from below, means to automatically hold the receptacle upon its manual placement into its operative position comprising a vertically movable member operated 45 by the manual shift of the receptacle, a switch for controlling the electric motor, and means for actuating the switch by the

50 manual shift of the receptacle before it reaches its operative position.

29. In a machine of the character described, the combination of a motor, a standard to the upper end of which the motor is secured, an agitator driven by the motor and supported from above with sufficient clearance to permit a receptacle with an open top to be placed into operative position around the agitator, means to secure the receptacle in operative position, and a guideway for the receptacle while it is being manually shifted, formed on the front 55 of the standard.

30. In a machine of the character described, the combination of an electric motor, a supporting column to the upper end of which the motor is secured, an agitator driven by the motor and supported from above with sufficient clearance to permit a receptacle with an open top to be manually placed into position around the agitator 60 from below, means to automatically hold the receptacle upon its placement into its operative position, and a receptacle guide integral with said column.

31. In a machine of the character described, the combination of an electric 65 motor, a supporting column to the upper end of which the motor is secured, an agitator driven by the motor and supported from above with sufficient clearance to permit a receptacle with an open top to be 70 manually placed into position around the agitator from below, means to automatically hold the receptacle upon its placement into its operative position comprising a member 75 integral with said column, and a receptacle 80 guide integral with said column.

32. In a machine of the character described, the combination of an electric motor, a supporting column to the upper end of which the motor is secured, an agitator driven by the motor and supported from above with sufficient clearance to permit a receptacle with an open top to be 85 manually placed into position around the agitator from below, and means to automatically hold the receptacle upon its manual placement into its operative position comprising a vertically movable member 90 shiftable by the upper portion of the receptacle and mounted directly in said column.

Signed at Newark, N. J., this 11th day of February, 1922.

RAYMOND B. GILCHRIST.
